UNITED STATES PATENT OFFICE.

WILLIAM B. BASTIAN, OF LOS ANGELES, CALIFORNIA.

QUICK-THROW THERMOSTAT VALVE.

Application filed May 11, 1926. Serial No. 108,248.

My invention relates to automatic quick throw valves and more particularly to thermostatically operated quick throw valves.

Various forms of automatic water heaters are in use at present for the purpose of providing a ready supply of hot water in residences and other buildings. One common form of automatic water heater comprises a hot water reservoir tank, a gas burner for heating the water in the tank, a valve for controlling the supply of gas to the burner, and a thermostat by which the gas supply is turned on when the temperature of the water falls below a certain point and which turns off the gas when the water has been heated above a certain temperature.

One of the chief difficulties experienced with this form of automatic water heater is in the functioning of the thermostatically operated valve. Many of these valves have been found to open slowly, for the first portion of their throw, at least, thus causing gas to flow from the burner for a short period of time at a less rate than necessary for the gas to be ignited by the pilot flame. This gas forms an explosive mixture in the burner chamber which either escapes into the surrounding atmosphere causing an obnoxious odor or, as has happened in many cases, it explodes, damaging the heater and setting fire to the house. Another undesirable result is that very often the flame will backfire and ignite in the mixing chamber, thus producing a flame which has practically no heat. This gas leakage due to slow opening of the burner valve is therefore not only wasteful but obnoxious and exceedingly dangerous.

It is an object of my invention to provide a novel quick throw valve unit which will move between open and closed position in a single quick movement, thus immediately allowing a full flow of fuel.

Most of the thermostatically operated quick throw valves as now manufactured are not only inefficient but are complicated, thus being subject to disorders and expensive to make.

It is another object to provide a simple thermostatically operated quick throw valve which has a small number of moving parts and is inexpensive to produce.

It is another object of my invention to provide a very simple quick throw valve in which a ball valve is operated by the constriction of a garter spring upon the spheri-

cal surface thereof, the valve not being likely to get out of order.

It is a further object of my invention to provide a novel thermostatic valve operating mechanism.

Other objects and advantages of my invention will be made manifest in the following description and the accompanying drawing in which:

65

Fig. 1 is a diagrammatic sectional view illustrating an automatic water heater with which my invention is incorporated.

Fig. 2 is a vertical sectional view taken on the line 2—2 of Fig. 1 and illustrating the quick throw thermostatic valve of my invention.

Fig. 3 is a fragmentary view corresponding to a portion of Fig. 2 and illustrating the valve of my invention in open position.

75

Fig. 4 is a horizontal sectional view taken on the line 4—4 of Fig. 2.

Referring specifically to the drawing, Fig. 1 shows an automatic heater 10 which has a hot water reservoir tank 11. This tank 11 is cylindrical in form and supported in upright position by a frame (not shown). The tank 11 has a head 13 at the upper end thereof and a floor plate 14 positioned in the lower end thereof, the head and floor members being secured to the tank 11 so as to form a tight hot water chamber 15. The head 13 and floor plate 14 are centrally apertured and a flue 16 is secured at opposite ends to the head 13 and the floor 14 so as to communicate with these apertures. A water heating retort 18 is disposed a short distance from the lower mouth of the flue 16. This retort is in the form of a metal casting cored out to form a central enclosed cavity 95 with the lower portion of which a cold water pipe 19 connects. The pipe 19 leads downward and by suitable connections reverses in direction so as to enter the floor 14, as indicated at 20, to communicate with the lower end of the hot water chamber 15. A hot water pipe 22 is threadedly received in the upper end of the retort 18, passes upward through the flue 16 and, reversing

in direction at the upper end of the tank 11, passes downward through the head 13 communicating with the upper end of the hot water chamber 15. Disposed about that portion of the cold water pipe 19 which connects with the retort 18 is a gas burner 24. Formed integrally with the gas burner 24 is a gas and air mixer 25 through which a

mixture of gas and air may be fed to the burner 24. A threaded opening 26 is formed in the floor 14 in which the thermostatically operated valve 28 of my invention 5 is screwed.

This thermostatically operated valve 28 has a housing 30 which has a body portion 31 in which is formed a tightly enclosed gas chamber 32. Access to this chamber 32 10 is had by removing a plate 32^a which is secured to the body 31 by screws 32^b. A supporting neck 33 is formed upon the upper wall of the housing body 31 and rises upward, as shown in Figs. 1 and 2, being provided with external threads 34 at the upper 15 end thereof suitable for tight threaded engagement with the threads formed in the opening 26. The neck 33 has an internal longitudinal cavity 35 opening from the gas 20 chamber 32. The cavity 35 is restricted at the upper end of the neck to form a threaded opening 36. Threadedly received in the opening 36 is the lower end of a thermostatic element 37. This thermostatic element 25 has a copper tube 38 which is threaded into the hole 36 at the lower end and which threadedly receives a plug 40 at the upper end thereof. As shown in Fig. 1, the tube 38 passes upward a considerable distance in 30 the hot water chamber 15 above the bottom 14 of the water heater 10. Screwed into a threaded aperture formed centrally in the plug 40 is a steel rod 42. This rod extends downward from the plug 40, through the 35 interior of the tube 38, through the neck 33, into the gas chamber 32 where it terminates at a pointed lower end 44, for a purpose which will be described later.

A gas inlet pipe 45 is provided in the 40 housing body 31 communicating with the gas chamber 32. A gas outlet pipe 46 is threadedly received in a threaded opening 47 formed in the lower wall 48 of the housing body 31, at the opposite end of the body 31 from the neck 33, and projecting from the body in an opposite direction than this neck. The gas outlet pipe 46 is provided with a shoulder 50 which compresses a gasket 51 against the wall 48 forming a tight 50 seat between the pipe 46 and the wall 48 when the pipe 46 is screwed tightly into the threaded opening 47. The gas outlet pipe 46 has a valve seat projection 53 which projects a slight distance upward into the gas chamber 32. A valve seat 54 is formed in the upper end of the projection 53 and communicates with the opening 55 of the outlet pipe 46. The outlet pipe 46 extends downward from the shoulder 50 and is bent 60 to form a horizontal portion 56 which is disposed directly beneath the gas and air mixer 25 of the burner 24. A nozzle 57 is provided upon the horizontal portion 56 of the pipe 46 in a suitable position for directing gas upward into the gas and air mixer 65

25. A gas cock 58 is provided in the end of the horizontal pipe portion 56, by the turning of which the flow of gas through the pipe portion 56 to the nozzle 57 may be shut off. 70

A stuffing box 60 is formed in the lower wall 48 at the opposite end of the body 31 from the opening 47 therein. The stuffing box is integrally formed with the body 41 and communicates with a threaded opening 75 61 which is adapted to receive the threaded stem 62 of a fulcrum screw 63 which has a thumb wheel 64 secured integrally upon the outer end of the stem. The stem 62 projects upward into the chamber 32 and has 80 a flat face 65 at its inner end. A centralizing pin 68 centrally projects from the face 65 of the fulcrum adjusting screw 63.

A lever 70 is adapted to be disposed in the gas chamber 32 and extends nearly from one 85 end to the other thereof. At one end of this lever a boss 71 is formed to project downward therefrom so that a knife fulcrum edge 72 rests in contact with the face 65 of the fulcrum screw 63. A hole 73 is formed in 90 the lever 70 on the line of the knife edge 72 to receive the pin 68 and retain the knife edge 72 in engagement with the face 65. An indentation 74 is formed in the upper 95 face of the lever 70 a short distance longitudinally inward from the position of the knife edge 72, this indentation being adapted to receive the pointed end 44 of the rod 42 so that a downward pressure may be exerted by the rod 42 upon the lever 70. 100

The opposite end of the lever 70 from the fulcrum 72 has an enlarged portion 78 which has a central aperture 79 vertically formed therein. The enlarged portion 78 is also split horizontally by a slot 80. The central aperture 79 is so formed as to be disposed above the valve seat 54 and to be moved through a definite arcuate path during a rocking of the lever 70 about the fulcrum 72. A spherical ball valve member 82 is 110 adapted to be disposed within the opening 79 during this rocking of the lever 70 and is therefore restricted to that arcuate path. The ball 82 and the valve seat projection 53 unite to form a ball valve 83. A garter spring 84 is adapted to be disposed in the slot 80 so as to encompass the spherical valve member 82 and to exert a constricting resilient pressure against this member. The lever 70 has a downward projection 85 formed on the lower face thereof so as to be disposed slightly inward from the enlarged portion 78. This projection 85 is adapted to receive the upper end of a compression spring 86, the lower end of which contacts the upper face of the lower housing wall 48 so as to resiliently urge the lever 70 upward. A hole 90 is vertically formed in the lever 70, this hole 90 passing centrally through the projection 85. A recess 92 is formed in the 120 125 130

upper face of the wall 48 directly beneath the mean position of the hole 90, and a threaded hole 93 is formed in the upper wall of the housing body 31 in vertical alignment with the recess 92. A lever guide member 95 is provided with threads so as to be threadedly received in the hole 93. The guide member 95 has a pin portion 96 which projects downward through the hole 90 so as to be seated at its lower end in the recess 92.

The operation of my invention is as follows:

In the automatic water heater 10 it is desired to maintain the water in the hot water chamber 15 at a temperature slightly below boiling. The heating of this water is accomplished by gas mixed with air in the gas and air mixer 25 and ignited as it flows from the burner 24 by a pilot flame supplied at the tip of a pilot gas pipe 100 which has a valved connection with the gas supply pipe 45 as shown in Fig. 1. In order for gas to be supplied to the burner 24 the spherical valve member 82 must be disposed away from the valve seat 54 in open position as shown in Fig. 3. When the valve member 82 is in this position, gas from the supply main 45 passes into the gas chamber 32 and between the valve member 82 and the valve seat 54 into the outlet pipe opening 55. Gas thus flows through the pipe 46 and is emitted therefrom through the nozzle 57 into the gas and air mixer 25. The flame proceeding upward from the burner 24 heats the retort 18 from which heated water moves upward through the pipe 22 forming a thermosiphonic circuit including the pipe 22, the hot water chamber 15, the cold water pipe 19, and the retort 18. Thus the hot water issues from the upper end of the pipe 22 into the upper end of the hot water chamber 15. As this continues, the amount of hot water in the upper end of the tank 11 increases in quantity and advances downward toward the floor 14 of the tank 11. When the hot water thus advancing downward covers a portion of the copper tube 38 of the thermostatic element 37, the thermostatic element 37 causes the valve member 82 to be seated upon the valve seat 54 as illustrated in Fig. 1 and in a manner which will be described later.

As the hot water is used through a service pipe 102 provided at the upper end of the tank 11, or as the water in the hot water chamber 15 cools off by radiation the water in the lower end of the tank 11, in which the thermostatic element 37 is disposed, becomes cool. With this decrease in temperature the copper tube 38 of the thermostatic element 37 contracts, thus causing a decrease in length. A steel rod 42 on the inside of the thermostatic element 37 also decreases in length with this decrease in temperature, but, owing to the difference in the coefficients of

expansion of the different metals of which the tube 38 and the rod 42 are formed, the tube 38 contracts a greater amount than the rod 42. This causes the lower pointed end of the rod 42 to be slowly and forcibly projected a slight distance downward from the position in which it is shown in Fig. 2. This causes the enlarged end 78 of the lever 70 to be moved downward from the position in which it is shown in Fig. 2 to the position in which it is shown in Fig. 3. This causes the garter spring 84 to be moved downward beyond the center of the ball 82. A resilient pressure of the garter spring 84, in a manner well known in the art, now causes the ball 82 to be thrown quickly from the seat 54 into the position in which it is shown in Fig. 3. Here the upward movement of the ball 82 is limited by contact with the lower surface of the upper wall of the housing body 31. This movement of the ball 82 opens the valve 83 and allows gas to pass from the supply main 45, through the chamber 32 and the outlet pipe 46 to the burner 24 in a flow of maximum rate. As this flow of gas at its maximum rate is mixed with air in the mixer 25 and is discharged from the burner 24, it at once bursts into flame and is completely consumed, heating the water in the retort 18 and setting up the thermosiphonic flow previously described. As the lower level of the hot water in the tank 11 moves downward the hot water surrounds a portion of the thermostatic element 37. This raises the temperature of the element 37 which causes a differential expansion of the copper tube 38 and the steel rod 42 resulting in the opposite effect from that caused by their cooling as above described; that is, the heating of the thermostatic element 37 results in the lower pointed end 44 of the steel rod 42 being drawn upward, which releases the lever 70 from the pressure of the rod 42. Thus released, the lever 70 responds to the upper pressure of the compression spring 86 and swings upward into the position in which it is shown in Fig. 2. As the lever 70 thus swings upward, the garter spring 84 passes over the surface of the ball 82 past the center thereof, thus causing a quick return of the ball 82 from its open position to its closed position. The operation of the thermostatic valve, above described, is for the purpose of shutting off the gas when the water in the tank 11 has been heated to a desired temperature and turning on the gas when the water has cooled below a predetermined temperature. The exact range of temperature over which it is desired that gas be supplied to the burner 24 may be determined at will by manual rotation of the fulcrum screw 63. When the screw 63 is screwed inward the valve 83 is caused to open and close at higher temperatures and vice versa.

One of the principal features of my in-

vention is the simplicity of the structure thereof, the fewness and cheapness of the parts making up this structure, permitting the economical manufacture of my thermos 5 statically operated quick throw valve.

I claim as my invention:

1. In a quick throw valve, the combination of: a spherical valve member; a valve seat upon which said member is adapted to rest; 10 means for limiting the movement of said member from said seat; a garter spring disposed about said member; and means for shifting said garter spring towards and away from said valve seat.
2. In a quick throw valve, the combination of: a spherical valve member; a valve seat upon which said member is adapted to rest; means for limiting the movement of said member from said seat; a garter spring disposed about said member; means for shifting said garter spring towards and away from said valve seat; and thermostatic 15 means for operating said shifting means.
3. In a quick throw valve, the combination of: a spherical valve member; a valve seat upon which said member is adapted to rest; means for restricting said member to movement in a given path; means for limiting the movement of said member from said seat; a garter spring disposed about said member; and means for shifting said garter spring towards and away from said valve seat.
4. In a quick throw valve, the combination of: a spherical valve member; a valve seat upon which said member is adapted to rest; means for restricting said member to movement in a given path; means for limiting the movement of said member from said seat; a garter spring disposed about said member; means for shifting said garter spring towards and away from said valve seat; and thermostatic means for operating said shifting means.
5. In a quick throw valve, the combination of: a housing providing a gas-tight chamber therein; a gas inlet, opening through said housing into said chamber; a gas outlet, opening through said housing from said chamber; a valve seat provided in said chamber to communicate with said outlet; a spherical valve member adapted to rest upon said valve seat; a garter spring for moving said spherical member to and from said seat; and means for operating said garter spring.
6. In a quick throw valve, the combination of: a housing providing a gas-tight chamber therein; a gas inlet, opening through said housing into said chamber; a gas outlet, opening through said housing from said chamber; a valve seat provided in said chamber to communicate with said outlet; a spherical valve member adapted to rest upon said valve seat; a garter spring for moving said spherical member to and from said seat; and means for operating said spherical member to and from said seat;

and a lever for operating said garter spring.

7. In a quick throw valve, the combination of: a housing providing a gas-tight chamber therein; a gas inlet, opening through said housing into said chamber; a gas outlet, opening through said housing from said chamber; a valve seat provided in said chamber to communicate with said outlet; a spherical valve member adapted to rest upon said valve seat; a garter spring for moving said spherical member to and from said seat; and a lever for operating said garter spring; and thermostatic means for moving said lever.

8. In a quick throw valve, the combination of: a housing providing a gas-tight chamber therein; a gas inlet opening through said housing into said chamber; a gas outlet, opening through said housing from said chamber; a valve seat provided in said chamber to communicate with said outlet; a spherical valve member adapted to rest upon said valve seat; a garter spring for moving said spherical member to and from said seat; a lever for operating said garter spring; thermostatic means for moving said lever; and means for determining the temperatures at which said thermostatic means will move said lever sufficiently to cause said garter spring to operate said valve member.

9. In a quick throw valve, the combination of: a housing providing a gas-tight chamber therein; a gas inlet, opening through said housing into said chamber; a gas outlet, opening through said housing from said chamber; a valve seat provided in said chamber to communicate with said outlet; a spherical valve member adapted to rest upon said valve seat; a garter spring for moving said spherical member to and from said seat; a lever for operating said garter spring; thermostatic means for moving said lever; and resilient means tending to move said lever against the tendency of said thermostatic means.

10. In a quick throw valve, the combination of: a housing providing a gas-tight chamber therein; a gas inlet opening through said housing into said chamber; a gas outlet, opening through said housing from said chamber; a valve seat provided in said chamber to communicate with said outlet; a spherical valve member adapted to rest upon said valve seat; a garter spring for moving said spherical member to and from said seat; a lever for operating said garter spring; thermostatic means for moving said lever; and an adjustable fulcrum provided for said lever for determining the temperatures at which said thermostatic means will move said lever sufficiently to cause said garter spring to operate said valve member.

In testimony whereof, I have hereunto set my hand at Los Angeles, California, this 5th day of May, 1926.

WILLIAM B. BASTIAN.
